UNITED STATES PATENT OFFICE.

TOBIAS E. RAFFEL, OF NEW YORK, N. Y.

CORRUGATED-PAPER-BOARD MACHINE.

1,189,737.

Specification of Letters Patent.

Patented July 4, 1916.

Application filed March 14, 1916. Serial No. 84,012.

To all whom it may concern:

Be it known that I, TOBIAS E. RAFFEL, a citizen of the United States, residing in the city, county, and State of New York, have 5 invented certain new and useful Improvements in Corrugated-Paper-Board Machines, of which the following is a specification.

My invention relates to a machine having 10 a pressing device which coacts with a heater, to apply a second facing to previously formed single-faced corrugated paper.

The objects of my invention are first, to 15 provide a pressing device of simple and novel construction; second, to provide means for producing a rubbing or ironing action of the pressing device on the sheets while they are being pasted and dried; and third, to 20 afford provision for raising the pressing device so as to permit of inserting the sheets between said device and the face of the heater. I attain these objects, as well as others not herein specifically enumerated, 25 by means of the apparatus illustrated in the accompanying drawings in which—

Figure 1 is a top plan view of an apparatus embodying my invention; Fig. 2 is a side elevation showing the pressing device 30 in normal relation to the heater; Fig. 3 is a similar view showing the pressing device raised and, Fig. 4 is a cross section on the line 4-4 of Fig. 1.

Similar numerals refer to similar parts 35 throughout the several views.

The heater 1 comprises a series of contiguous chests in which steam or other heating medium is circulated. Said heater has a smooth upper surface, over which the 40 sheets are drawn by means of one or more pairs of drawing rolls 2. The second facing sheet travels adjacent to the surface of the heater, and the single-faced sheet is imposed thereon with its unfaced surface 45 downward and in contact with said second facing. In passing to the heater the single-faced sheet travels over a suitable paste applying device, not shown, whereby silicate or other adhesive is applied to the crowns 50 of the unfaced corrugations. As the sheets are drawn over the heater, whereby they are dried, sufficient pressure is applied thereon, by means of the pressing device hereinafter described, to paste them together.

55 The pressing device has a pair of supporting members 3, which, in the present in-

stance, are made of angle bars, mounted adjacent to the lateral edges of the heater and movable endwise thereon. Extending across said members and loosely carried on the pins 5 thereof are a series of presser plates 6, which bear on the upper surface of the composite sheet with sufficient pressure to paste the sheets together without crushing the intermediate corrugations. The plates 6 60 are free to move vertically on the pins 5, and, accordingly, they will accommodate themselves to variations in the height of the corrugations. The lower edges of the plates are preferably rounded off, as shown, to 65 prevent tearing the paper.

The presser plates are arranged to produce a rubbing or ironing action on the sheets as they are being pasted together. Such action facilitates the pasting operation and smooths out any wrinkles, unevenness or air bubbles in the sheets while they are being dried in passage over the heater. To this end, I provide suitable means for reciprocating the plate supporting members 75 3 in opposite directions to each other. It is obvious, that such alternating movement of the supporting members will cause a vibratory or oscillatory movement of the plates carried thereon, as is indicated by the plate 80 3 shown in dot and dash lines in Fig. 1.

The means which I preferably employ for reciprocating the members 3 comprises a pair of eccentrics or cams 7, mounted to rotate with the shaft 8 and provided with 90 grooves 9, in which ride rollers 10 fixed to the forks 11. The lower end of each fork is pivoted at 12 to a rocker-arm 13, which is pivoted at 14 to the heater or framework of the machine. The rocker-arm has a slot 95 15, in which rides a roller 16, extending laterally from the members 3. Collars 17 are provided to hold the rollers 10 in the cam grooves. As the cams 7 rotate, the forked connectors 11 will rock the arms 13 100 to and fro and produce reciprocating movement of the members 3. The two cams are preferably set 180° apart so as to cause alternate movement of the members 3. By adjusting the angular relation of the cams 105 to each other, the relative movement of the two members 3 may be varied as desired, with a corresponding variation in the movement of the presser plates.

Before starting the machine, it is desirable 110 to lift the pressing device clear of the heater, so as to permit of freely inserting the sheets

therebetween. For that purpose I provide two pairs of cranks 18, connected together by pivoted rods 19, each pair of cranks being fixed to a cross shaft 20, which shafts are borne in suitable standards. One of the cranks has a handle lever 21, whereby all of the cranks may be operated together. Pivoted links 22 connect the supporting members 3 with the cranks 18. By pulling downward on the handle 21, the pressing device will be raised from the heater as shown in Fig. 3. A pair of slides 23, pivoted at 24 to the heater and having slots 25, in which ride the rollers 26, fixed to the members 3, are provided to guide the movement of the forward portions of said members.

I have hereinbefore described a preferred form of my apparatus, but it will be understood that various modifications may be made in the arrangement and construction of the parts thereof without departing from the spirit and scope of my invention.

What I claim is:

1. In a machine of the character specified, the combination of a heater, a supporting member mounted for longitudinal reciprocating motion adjacent to each side of the heater, presser plates laid across said members and held thereon for movement therewith, and means for reciprocating said supporting members in opposite directions, whereby to produce oscillation of the plates.
2. In a machine of the character specified, the combination of a heater, a supporting member mounted for longitudinal reciprocating motion adjacent to each side of the heater, presser plates laid across said members and held thereon for movement therewith, said plates being free to move vertically, and means for reciprocating said supporting members in opposite directions, whereby to produce oscillation of the plates.
3. In a machine of the character specified, the combination of a heater, means for drawing the sheets over the heater, a pressing device bearing on the upper surface of the

sheets and movable with an oscillating motion thereon, and means for actuating the pressing device.

4. In a machine of the character specified, 50 the combination of a heater, drawing rolls for progressing a composite sheet over the heater, a pressing device having a series of plates which bear loosely on the upper surface of the sheet and are movable thereon 55 with an oscillatory motion and means for actuating the pressing device.

5. In a machine of the character specified, the combination of a heater having a smooth face, presser plates extending transversely 60 across the face of the heater, endwise movable supports engaging the plates near their ends, and means for reciprocating both supports in opposite directions to each other.

6. In a machine of the character specified, 65 the combination of a heater, endwise movable supports mounted at the sides of the heater, presser plates carried thereon and extending transversely across the heater, and means engaging with the supports for 70 raising and lowering the plates relative to the heater.

7. In a machine of the character specified, the combination of a heater, a pair of bars mounted to move longitudinally of the 75 heater, each provided with a series of vertical pins, presser plates mounted on the bars and extending transversely across the heater, said plates having perforations through which the pins pass, and means for continuously reciprocating said bars in alternate relation to each other, whereby to produce oscillation of the plates.

8. In a machine of the character specified, 85 a heater, a pair of supports mounted at the sides of the heater and movable longitudinally, presser plates mounted on the supports for movement therewith and extending transversely across the heater, and means for reciprocating the supports.

TOBIAS E. RAFFEL.
